UNITED STATES PATENT OFFICE

168,648

COMBINED HAT AND PUPPET

Frances Glencott, New York, N. Y.

Application April 26, 1951, Serial No. 14,971

Term of patent 14 years

(Cl. D3—13)

To all whom it may concern:

Be it known that I, Frances Glencott, a citizen of the United States, residing in the city of New York, State of New York, have invented a new, original, and ornamental Design for a Combined Hat and Puppet, of which the following is a specification, reference being had to the accompanying drawings, forming part thereof.

I claim:

The ornamental design for a combined hat and puppet, substantially as shown.

FRANCES GLENCOOT.
